DESIGN FOR A FINGER RING

Otto Grun, New York, N. Y.

Application December 11, 1944, Serial No. 116,838

Term of patent 14 years

(Cl. D45—10)

To all whom it may concern:

Be it known that I, Otto Grun, a citizen of the United States, residing in the Borough of Manhattan, city, county, and State of New York, have invented a new, original, and ornamental Design for a Finger Ring, of which the following is a specification, reference being had to the accompanying drawing, forming part thereof.

On the drawing,

Fig. 1 is a front elevational view of a finger ring embodying my design;

Fig. 2 is a side elevational view of the finger ring shown in Fig. 1;

Fig. 3 is an elevational view of the ring shown

in Fig. 1, looking at the ring from a direction opposite to that of Fig. 1;

Fig. 4 is a top plan view of the ring, as seen looking down upon the ring in Fig. 2;

Fig. 5 is a vertical cross-sectional view of the ring, on the line 5—5 of Fig. 4; and

Fig. 6 is a view in perspective of the ring, the ring being turned slightly out of the position of Fig. 2.

I claim:

The ornamental design for a finger ring, as shown,

OTTO GRUN.
